UNITED STATES PATENT OFFICE.

ALBERT W. CONNOR, OF ST. LOUIS, MISSOURI, ASSIGNOR TO SIMMONS HARDWARE COMPANY, OF ST. LOUIS, MISSOURI, A CORPORATION.

COMBINED CARD AND BOOK FOR HOLDING FISH-HOOKS.

SPECIFICATION forming part of Letters Patent No. 726,509, dated April 28, 1903.

Application filed December 22, 1902. Serial No. 136,094. (No model.)

To all whom it may concern:

Be it known that I, ALBERT W. CONNOR, a citizen of the United States, residing in the city of St. Louis, in the State of Missouri, have 5 invented certain new and useful Improvements in a Combined Card and Book for Holding Fish-Hooks, of which the following is a full, clear, and exact description, reference being had to the accompanying drawings, 10 forming part of this specification.

My invention relates to a card that also serves as a book for holding fly or other fish hooks.

My invention consists in features of novelty 15 hereinafter fully described, and pointed out in the claims.

Figure I is a perspective view of my improved card and book for holding fish-hooks, the same being shown in its folded position.

Fig. II is a front view of the article in its open 20 position.

Referring to the drawings, 1 represents a card divided into sections 2 by lines of perforations 3. One end of the card is provided 25 with a flap 4, adapted to be turned down over the loop ends of the leaders 5 of the hooks and to be gummed to the body 1 of the card between the lines A and B, thus forming pockets 4^a, that receive the loop ends of the leaders.

The lines 3 of perforations extend 30 through the flap 4, as shown in Fig. II. The body of the card is cut away at 6 and 7 to receive the hooks and the hook ends of the leaders, as clearly shown in Fig. II, and which

in itself is a common practice in the manufacture of fly-hook cards. The other end of 35 the card from the flap 4 is provided with a flap 8, adapted to be folded over the hooks, as shown by dotted lines in Fig. II; but this

flap is not designed to be gummed to the body 40 of the card, but is free to be opened out to expose the hooks. The lines 3 of perforations

pass through the flap 8, as shown in Fig. II, so that each hook and leader is mounted on a section 2 of the card, each section having 45 its pocket 4^a and loose flap 8^a, so that when the sections are separated each one is complete in itself and each holds its fish-hook and leader snugly in position and protects the point of the hook from engagement with other 50 things.

When the combined card and book has been filled, it may be folded into the position shown in Fig. I, in which position it can be conveniently handled.

55 I claim as my invention—

1. In a combined card and book for fish-hooks, the combination of a card divided into sections by perforations, a single flap provided with perforations coincident with the 60 perforations of the card, gummed to the body of the card at several points to form a plurality of pockets at one end of the card to receive the loop ends of the leaders, and a single flap at the other end of the card also provided with perforations coincident with the 65 perforations of the card and adapted to be folded over onto the body of the card to cover the hooks.

2. In a combined card and book for fish-hooks, the combination of a card provided with a single flap at one end adapted to be gummed at several points to the body of the card to form a plurality of pockets to receive the loop ends of the leaders, and a single flap 70 at the other end of the card adapted to be folded over onto the body of the card to cover all of the hooks, substantially as set forth.

In testimony whereof I have hereunto set my hand this 17th day of December, 1902. 80

ALBERT W. CONNOR.

In presence of—

E. S. KNIGHT,
M. P. SMITH.
